Primary Examiner — Brett Miller(74) *Attorney, Agent, or Firm* — Kirton McConkie; Brian Tucker(57) **CLAIM**

The ornamental design for a studio, as shown.

DESCRIPTION

FIG. 1 is a top perspective view of a studio showing the claimed design;

FIG. 2 is a top plan view thereof;

FIG. 3 is a cross-sectional front elevation view thereof; the cross-sectional rear elevation view thereof being identical; and,

FIG. 4 is a cross-sectional right elevation view thereof; the cross-sectional left elevation view thereof being identical. A bottom view of the studio is omitted because the bottom of the studio is flat and lacks surface ornamentation.
